(57) **CLAIM**

The ornamental design for a multi-purpose pillow, as shown and described.

DESCRIPTION

FIG. 1 is a perspective view of a multi-purpose pillow, showing my new design;

FIG. 2 is a top plan view thereof;

FIG. 3 is a bottom plan view thereof;

FIG. 4 is a side elevational view thereof;

FIG. 5 is a top plan view, showing an alternate embodiment of my new design;

FIG. 6 is a bottom plan view thereof;

FIG. 7 is a left side elevational view thereof; and,

FIG. 8 is a right side elevational view thereof.

The broken lines are for environmental purposes only and form no part of the claimed design.
